UNITED STATES PATENT OFFICE

PATRICK W. SHIELDS, OF PITTSBURGH, PENNSYLVANIA, ASSIGNOR TO MCKENNA
BRASS & MANUFACTURING COMPANY, INC., OF PITTSBURGH, PENNSYLVANIA, A
CORPORATION OF PENNSYLVANIA

APPARATUS FOR FILLING BOTTLES

Application filed May 8, 1926. Serial No. 107,610.

This invention relates to apparatus for filling bottles, and is particularly useful in connection with a bottle filling machine having a plurality of stationary filling heads.

I provide a bottle filling machine including a plurality of filling heads, a conveyor adapted to carry bottles in a plurality of paths alongside the heads, and means for moving bottles from the several paths sidewise to the filling heads. I further provide for gripping the bottles during such sidewise movement while carrying them into filling alignment with the filling head and also for gripping them to assist in the removal of the bottles from the filling head. The bottles are thereafter preferably moved a further distance sidewise to take them out of filling alignment with the head and onto another conveyor by which they are moved away from the filling machine.

Preferably the bottles for the several heads are supplied in substantially parallel paths spaced different distances from the filling heads, and means are provided for moving the bottles sidewise in different amounts to bring them into substantially identical positions with respect to the several heads. Associated with each head I provide a feeding means for moving the positioned bottles sidewise into filling alignment. This means preferably comprises a pair of pivoted arms having a common axis, the arms being movable relative to one another to grip the bottles and movable together to shift the gripped bottles to the desired position. The arms preferably rotate from a position on one side of the filling head across the axis of the head proper to a position on the opposite side of the filling head, suitable provision being made for interrupting this movement to permit filling of the bottle when the bottle is in filling alignment with the head.

Further provision is made for accomplishing this movement of the arms through yielding means, such as springs, so that the gripping of the bottles and the movement thereof is accomplished in such manner that bottles of varying size may be handled and danger of breakage from jamming of the machine is eliminated.

I further provide a novel arrangement of the driving mechanism and also various other features of adjustment, all of which are valuable in apparatus of this character.

In the accompanying drawings:

Figure 1 is a front elevation of a two-head bottling machine embodying a present preferred form of my invention with the cover on the lower portion of the mechanism broken away;

Figure 2 is a back elevation to enlarged scale of the lower portion of the apparatus shown in Figure 1, the cover being removed;

Figure 3 is a horizontal section on the line III—III of Figures 1 and 2;

Figure 4 is a horizontal section on the line IV—IV of Figure 2;

Figure 5 is an end view, partly broken away, of the apparatus shown in Figure 2;

Figure 6 is a vertical section, partly broken away, on the line VI—VI of Figure 2;

Figure 7 is a vertical section, partly broken away, on the line VII—VII of Figure 6;

Figure 8 is a horizontal section, partly broken away, on the line VIII—VIII of Figure 7;

Figure 9 is a vertical section on the line IX—IX of Figure 8;

Figure 10 is an elevation, partly broken away, of the spring barrel shown in the upper right hand portion of Figure 7; and

Figure 11 is a view taken at right angles to Figure 10.

In the illustrated embodiment of my invention there is shown a bottling machine having a pair of stationary bottling heads indicated generally by the reference characters 2 and 3. The construction of these heads does not form a part of my present invention, and the preferred form of bottling head is fully described in my co-pending application, Ser. No. 222,573, filed Mar. 15, 1918. Each of these heads is provided with a plunger 4 adapted to move a bottle axially into the filling head proper whereupon the steps of

charging the bottle with a measured amount of syrup and filling the bottle with carbonated water to a desired height are carried out automatically by the filling head. As will be seen on reference to my co-pending appli-

cation, Ser. No. 222,573, filed March 15, 1918, above referred to, the entire head is lifted during this filling operation and for a portion of the time the head is locked in this raised position by an oil cylinder 5 actuated by a valve rod 6. With the head in locked position the plunger 4 is retracted somewhat, lowering the bottle part way out of the head and permitting the feeding of a cap thereabove. The plunger 4 is then again moved upwardly to force the cap into a crowning die, thus capping the bottle under pressure. The plunger 4 is then lowered to permit removal of the filled bottle from the head.

15 Referring now to Figure 3, there is shown a conveyor 7 which extends to any desired point from which it may be desired to feed bottles. The conveyor 7 comprises a chain flight 8 adapted to feed bottles to the head 2 and a chain flight 9 adapted to feed bottles to the head 3. The reference characters 2 and 3 have been applied to this view to indicate the heads corresponding to the portions of the apparatus actually shown in the view. 20 25 It will be understood that the heads proper lie above the apparatus shown herein.

The bottles which are supplied to the chain flight 8 are carried toward the head 2, and finally the leading bottle engages a fixed arm 10 which serves to move the bottle sidewise and into the position indicated in dotted lines on the drawings. The bottles which are supplied on the chain flight 9 move toward the head 3 until they engage a deflector 11 which shifts the bottles sidewise onto the chain flight 8, and the bottles are thus urged to a position relative to the head 3 substantially identical with the position taken by the bottles initially supplied on the chain flight 8 relative to the head 2.

30 35 It will be observed that the structure shown is capable of almost unlimited duplication so that bottles may be moved sidewise in varying amounts to the several heads, and that the apparatus is therefore adaptable to machines having more heads than two, as this simply involves supplying additional chain flights and additional deflectors. It will be observed that the bottles are supplied in paths substantially parallel to the length of the heads. It is found that this structure provides an exceedingly convenient and compact form of apparatus.

The arm 10 associated with the head 2 and the arm 10^a associated with the head 3 are each provided with a stop finger 12 as shown in Figure 3. These fingers fit in slots in the arms and are hinged for movement vertically so that they may be swung into or out of the path of the moving bottles. The finger which is associated with the head 2 is shown in raised position to permit passage of the bottles to the head, while the finger which is associated with the head 3 is shown in lowered position to prevent feeding of the bottles to

this head. With this arrangement any number of heads may be cut out of operation as desired.

Associated with each head is a pair of feeding arms 13 and 14. The arms are pivoted on the same axis and are arranged for movement relative to one another, and are also arranged for movement together. A link 15 is pivoted in the arm 13 at 16 and a link 17 is pivoted in the arm 14 at 18. The links 15 and 17 are pivotally connected at 19. It will be seen that when the arms 13 and 14 are swung toward one another the arm 13 and the link 15, and the arm 14 and the link 17 are each capable of gripping and moving a bottle sidewise. The feeding operation may be followed on Figure 3, and is as follows:

The bottles are supplied by the conveyor to a position adjacent the feeding head, the tendency of the conveyor always being to move the leading bottle to the position indicated in dotted lines for the filling head 2. The arm 13 is provided with a portion 20 which prevents the leading bottle from moving into this position when the arm is rotated to the position shown in Figure 3 so that the leading bottle cannot advance until the arm 13 has been rotated clockwise as viewed in the drawing to permit movement of the bottle to a position between the arm 13 and the link 15. At this time the arms 13 and 14 are spread apart so that the bottle is free to move into a position where it may be gripped. The arms 13 and 14 move relative to one another and this causes the bottle to be gripped between the arm 13 and the link 15. A spring clip 21 mounted on the link 15 assists in the gripping action. The arms 13 and 14 are then rotated together in a counter-clockwise direction as viewed in the drawing, thus moving the gripped bottle over the plunger 4 and into filling alignment with the head. The arms 13 and 14 then rotate away from one another, freeing the bottle by leaving it in position to be filled. The arms 13 and 14 are then both rotated clockwise, the links 15 and 17 being retracted a sufficient amount from the preceding operation to permit the tip of the link 17 to clear the bottle.

100 105 During this operation the next bottle on the conveyor has been pressing against the portion 20 on the arm 13 and when the arm is again moved clockwise the bottle moves into position between the arm 13 and the link 15 as above described. On the next relative movement of the arms the last mentioned bottle is gripped for sidewise movement onto the plunger 4 while the bottle already on the plunger is gripped between the arm 14 and the link 17 for sidewise movement to the discharge conveyor. The counter-clockwise movement of the arms then takes place as already described, movement of the first bottle being continued a sufficient distance

to take it to the conveyor and movement of the second bottle being carried out a sufficient distance to place it in filling alignment.

The arms are also capable of vertical movement with the plunger 4, and they thus serve to grip the bottle for its discharge movement while the bottle is still engaged in the filling head. It will be understood that in machines of this character there is some tendency for the bottle to stick in the head due to the action of the crowning die and also due to the throat rubber. The arms are therefore effective not only for moving the bottles sidewise but also for gripping them to assist in their axial movement to free them from the filling head. After the filled bottle has been moved sidewise as above described, the relative opening movement of the arms again takes place and the bottle is free to move to the right as viewed in the drawings on a conveyor 22. The conveyor 22 carries the bottles from between the arm 14 and the link 17 and toward an accumulator table 23 from which they are removed by hand and cased. In order to prevent interference between the filled bottles from the several heads, deflectors 24 and 24^a are provided for the heads. The drawing shows the deflector 24^a of the head 2 extended a sufficient distance to guide all the bottles from the several heads all the way across the conveyor and onto the accumulator table.

The following parts of the machine will now be described in detail and in the order named:

- (a) The conveyor mechanism.
- (b) The feeding arm mechanism.
- (c) The drive mechanism.

The conveyor mechanism

The conveyors 7 and 22 must be driven in the direction indicated in the arrows in such a manner as to keep the upper portion of the chain flights taut and the accumulator table 23 must be rotated in the direction of the arrow. There is provided a vertically extending drive shaft 25 connected to a horizontal main shaft 26 near the bottom of the machine (Figure 2) through miter gears 27. At the top of the shaft 25 connection is made through miter gears 28 to a head shaft 29 which carries sprockets not shown for driving the conveyor 22. The chain belts of the conveyor 22 extend from the head shaft 29 to a tail shaft 30 and the tail shaft is driven from the head shaft through the conveyor itself. The tail shaft 30 carries a miter gear 31 which drives an idler 32. The idler in turn drives a miter gear 33 which is connected to the head shaft 34 of the conveyor 7. The tail shaft 35 of the conveyor 7 is an idler shaft.

From the above it will be seen that the conveyors 22 and 7 are driven in the proper direction and that the upper portions of the chains are maintained taut at all times.

Suitable guides 36, 37, and 38 are provided for defining the course of the bottles.

The accumulator table 23 is driven from the shaft 29 through suitable gearing 39 shown in dotted lines in Figure 3.

The entire conveyor mechanism is mounted on a frame 40 which provides a suitable support for the conveyor chains, carries the guides 36, 37 and 38 and is movable up or down to make adjustment for bottles of different sizes. The table is mounted on a pair of jack screws 41 lying in the line of the two filling heads. Each of these jack screws is provided with a worm wheel 42 meshing with a worm 43 on a shaft 44. The shaft 44 is mounted on the base 40 and is provided with a projecting portion 45 adapted to receive a hand crank not shown. When the hand crank is turned the jack screws 41 are rotated and serve to raise or lower the table as desired to provide for bottles of different heights.

The accumulator table 23 is carried on a supporting member 46 which is loosely mounted on top of a jack screw 47. The jack screw 47 is threaded into a bracket 48 attached to the main frame of the machine. The jack screw 47 is provided with a worm wheel 49 which meshes with a worm not shown secured to a shaft 50. The shaft 50 is connected to the shaft 44 through a sprocket chain 51 so that rotation of the shaft 44 and consequent raising of the table also causes rotation of the shaft 50 and raising of the accumulator table to keep it at the same height as the conveyors at all times. In order to prevent rotation of the supporting member 46 there is provided a downwardly extending rod 52 which slides in the portion 48^a of the bracket 48 (Figure 1).

Obviously any vertical adjustment of the table will necessitate a relative movement of the shaft 25 and one of the gears mounted thereon. As shown in Figure 2 in dotted lines the miter gear 27 makes a spline connection with the shaft 25 so that the table may be adjusted in any desired amount without interfering with the driving connection.

The feeding arm mechanism

The arm 14 is mounted on a sleeve 53 surrounding a rod 54 which connects the base portion of the machine with the head thereof and which rod forms no part of the present invention beyond supplying a convenient manner of mounting certain of the mechanism. The sleeve 53 extends downwardly through the conveyor frame 40 and carries at its lower end a pinion 55. A rack 56 engages the pinion 55, and movement of the rack 56 is effective for rotating the arm 14. The rack 56 is carried on a supporting frame 57 and is held in place by guide rollers 58 and a cover plate 59. The guide rollers 58 are toothed and the back of the rack is corre-

spondingly toothed as I have found that smooth rollers have a tendency to wear flat whereas the rack and pinion form of roller guide above described is found to give no trouble whatever in service and to insure long life.

The arm 13 is mounted on a sleeve 60 which surrounds the sleeve 53. This sleeve also extends downwardly and is surrounded by a collar 61 mounted in the table 40. In the lower end of the sleeve 60 there is mounted a pinion 62 engaging a rack 63 which is similar to the rack 56. The collar 61 prevents water and broken glass from entering the mechanism below the table 40.

10 Rotatably mounted on the upper end of the sleeve 53 is a spring barrel 64 containing a coil spring 65, the inner end of which is secured to the sleeve 53 and the outer end of which is secured to the spring barrel 64 through a pin 66. The lower face of the spring barrel 64 is provided with ratchet teeth 67 engaging a pawl 68. The pawl 68 is secured to the arm 13 and it will be clear from Figures 10 and 11 that the spring barrel may be wound up so that the spring 65 will tend to rotate the arm 13 relative to the sleeve 53 and therefore relative to the arm 14. The sense of this relative rotation is such that the arms 13 and 14 always tend to rotate toward one another and the gripping action of the arms is due entirely to this yieldable spring. Therefore the apparatus is capable of handling varying diameters of bottles without adjustment of any sort.

15 The racks 56 and 63 each carry a roller 69. These rollers bear against pushers 70 and 71 by reason of the tendency of the coil spring 65 to expand. It will be clear that movement of the pushers 70 and 71 will be effective for moving the arms 13 and 14 relative to one another or relative to the stationary parts of the machine as is required for the operations previously set forth. The pushers 70 and 71 are 20 mounted in a bearing block 72 secured to the frame and they are each provided with a forked block 73 engaging a pin 74 on one arm of a bell crank 75. The bell cranks 75 are pivoted at 76 and are provided on their other arms with rollers 77 bearing against cams 78 and 79 mounted on the main shaft 25 26. Tension springs 80 secured to the bell cranks urge the pushers 70 and 71 against the rollers 69 and these springs are effective for overcoming the coil spring 65 so that the tendency of the mechanism just described is to open the feeding arms 13 and 14 as wide as possible. The closing of the arms can only be effected by the spring 65 when one or both of the pushers 30 35 40 45 50 55 60 65 70 75 80 85 90 95 100 105 110 115 120 125 130 70 and 71 are retracted somewhat by one or both of the cams 78 and 79. The cams 78 and 79 are so designed as to cause movement of the arms in the manner heretofore described. It is not deemed necessary to describe the various portions of these cams in detail as the

object to be attained by them will be clear. The cams are effective for permitting the springs 80 to overcome the action of the spring 65 so as to open the feeding arms 13 and 14; to retract the pushers 70 and 71 against the force of the springs 80; thus permitting the spring 65 to close the arms 13 and 14 and grip the bottles in the machine and to cause relative movement of the pushers 70 and 71 so as to determine the position of the arms 13 and 14 for the purpose of supplying bottles to the arms, and also to cause relative movement of the arms to effect feeding of bottles to and from the filling heads.

10 From the foregoing it will be clear that the feeding action of the arms is accomplished entirely through the yielding springs. This makes the apparatus capable of handling varying sizes of bottles without adjustment of any sort and also insures that no bottles will be broken if a jam should occur for any reason. If a bottle, for example, should stick in the head the springs 80 would simply fail to function and the bottle could be removed without doing any harm whatever to the bottle or the mechanism. It will be understood that the followers 77 are not necessarily in contact with the cams 78 and 79 at all times. These cams cause the arms 13 and 14 to open, this action taking place when the high points of a cam bears against its follower 77. After such high point has passed the follower, the spring 65 is free to bring the arms 13 and 14 together. It is effective for closing the arms until such closing movement is checked by a bottle. This limitation on the closing of the arms imposes a corresponding limitation on the movement of an arm 75, thus causing the follower roller 77 to ride clear of the lower points on its cam. By reason of this provision the arms are effective for gripping bottles of different sizes.

15 As above stated, it is desirable to grip the bottles during their removal from the filling head and provision is therefore made for moving the gripping arms 13 and 14 vertically with the bottles. This is accomplished by mounting the supporting frame 57 which carries the racks 56 and 63 and also supports the sleeves 53 and 60, on the bottle plunger 4. The frame 57 is provided with a lug 81 which fits into the side of the member 4^a, forming a part of the plunger 4 and secured therein by screws 81^a. The member 4^a is carried in a tubular guide 82 which has a slot 83 in the side thereof to accommodate the lug 81. It will be clear that as the plunger 4 moves upwardly to raise the bottle to filling position in the head, the arms 13 and 14 will also move upwardly. When the plunger 4 is moved downwardly to permit retraction of the bottle from the filling head, the arms 13 and 14 also move downwardly, and the timing of the cams 78 and 79 is such that at this time the filled bottle is gripped between the arm 14

and the link 17. At this time an empty bottle is engaged between the arm 13 and the link 15, but since these parts are made of smooth metal the arm and the link are free to slide downwardly over the bottle. The arm 14, however, is provided with rubber grippers 84 so that the filled bottle is firmly gripped and pulled out of the filling head in case there is any tendency for the bottle to stick therein.

It will be clear from Figure 5 that the vertical movement of the gripping arms and their associated mechanism is entirely independent of the pushers 70 and 71 since the vertical faces of these pushers will engage the rollers 69 at any point along the pushers and the movement of the arms can therefore be accomplished regardless of their vertical position.

Reference has already been made to the vertical adjustment of the conveyor frame 40 to adapt the machine for different sized bottles. It will be clear that such adjustment necessitates a corresponding adjustment of the height of the plunger 4 and the feeding arms 13 and 14. The apparatus for accomplishing this is clearly shown in Figures 6 and 7.

The plunger 4 comprises a lower portion 4^b carrying a cam follower 4^c which is engaged by the bottle cam 4^d mounted on the main shaft 26. Threaded into the member 4^b is a jack screw 85 having a flange 86 which supports the member 4^a. The member 4^a is surrounded at its upper portion with a sleeve 87 carrying a plug 88 upon which the bottles rest during the feeding operation. Underneath this plug 88 is a rubber 89 which rests on top of the jack screw 85. The sleeve 87 is carried in a bearing 90 which is mounted in the conveyor frame 40 and makes a sliding fit in the tubular bearing 82. The bearing 90 is movable up and down with the table 40 and provides a bearing near the top of the plunger 4. As clearly shown in Figure 3 the bearing 90 is screwed to the conveyor frame 40 and extends across the frame to the conveyors 9 and 22. The top of the bearing 90 is at the same level as the conveyor chains so that the bottles can be readily moved from one conveyor across the machine and onto the other conveyor (Figure 7).

When it is desired to adjust the machine to accommodate bottles of a height differing from those previously handled, the main shaft 26 is rotated until the plunger 4 is at its highest position and this exposes a screw 91 which is threaded in the member 4^a and whose head fits in an opening 92 in the sleeve 87. The screw 91 is provided with a flange 93 so that when the screw is threaded out of the hole in the member 4^a this flange engages the inner face of the tube 87 and prevents movement thereof. By turning the screw 91 further into its hole in the member 4^a the

sleeve 87 is freed and may be removed bodily to expose the adjusting mechanism. When the sleeve which carries the plug 88 and the rubber 89 has been removed the upper end of the jack screw 85 is exposed. The jack screw carries at its upper end a nut 94 which, when screwed down onto the jack screw, prevents any movement of the jack screw with respect to the member 4^a. The nut 94 is provided with a cross-wise slot, as is the upper end of the jack screw 85. The nut 94 is prevented from rotation with respect to the jack screw 85 by a bar 95 which fits into these two slots.

When the height of the plunger is to be adjusted, the bar 95 is removed and the nut 94 is loosened. A large screw driver or similar tool is then inserted in the slot in the upper end of the jack screw 85 and the jack screw is rotated a desired amount to raise or lower the upper portion of the plunger 4. After the desired adjustment has been made, the nut 94 is again tightened, the bar 95 is put in place, the sleeve 87 is placed over the upper end of the member 4^a and the screw 91 is threaded outwardly to hold the sleeve tightly in place. It will be clear that when the jack screw is rotated so as to alter the relative position of the members 4^a and 4^b, the supporting frame 57 which carries the feeding arms and the sleeves on which they are mounted will also be moved with the member 4^a.

The drive mechanism

The prime mover for the machine is an electric motor 96. In addition to the usual hand switch there is provided a safety switch mounted in a switch box 97 (Figure 2). The switch is provided with a switch arm 98 carrying a roller 99 which bears against a cam 100. The cam 100 is secured to a sleeve 101 which is mounted on a rod 54^a forming a part of the head supporting structure. The sleeve 101 extends upwardly through the frame 40 (Figure 7) and is surrounded for a distance above the frame by a tube 102. This tube is secured in the table 40 and extends a sufficient distance thereabove to exclude any water or broken glass from the space below the table. Carried on the upper end of the sleeve 101 is a lever 103 which extends outwardly over the conveyor 7 and acts as a gauge for the bottles being fed to the machine. If a high bottle is supplied to the machine, the neck of such bottle will engage the arm 103, rotating the sleeve 101 with the attached cam 100 and opening the switch to stop the motor 96.

Additional safety is provided by a limit switch 104 secured to the upper portion of the machine and adapted to be engaged by lugs 105 mounted on the machine heads (Figure 1). In case a bottle is not fed into exact filling alignment with a head but is

nevertheless a sufficient distance over the plunger 4 that the bottle will be raised, the upper portion of the bottle will in all probability bear against the lower portion of the filling head and tend to raise the same far beyond the normal distance. In such case the lug 105 on the head affected will engage the switch 104 and stop the motor before any damage is done.

10 The motor 96 is connected to a jack shaft 106 through a silent chain drive 107. The sprocket of the chain drive which is mounted on the shaft 106 is preferably connected thereto through a shear pin arrangement 108 so that any jamming of the mechanism which is not prevented by the safety means already described can do no harm other than the shearing of the pin. A hand wheel 109 is also secured to the shaft 106 to permit manual operation of the machine for purposes of adjusting. The jack shaft 106 has keyed thereon a pinion 110 engaging a gear 111 mounted on a shaft 112. The shaft 112 is carried in an adjustable frame 113 pivoted on a shaft 114 and having a clamping screw 115 at its upper end. This clamping screw 115 has a shoulder 116 and has a threaded portion 117 passing through a slot 118 in a frame bracket 119. With this arrangement 20 the shaft 112 may be moved toward or away from the shaft 106 so that the gear 111 may be removed and a gear of a different size substituted therefor so as to vary the speed of the machine as desired. The gear 111 is secured to the shaft 112 by a bolt 120 threaded into the end of the shaft 112 and removal of this bolt permits ready replacement of the gear 111. Also mounted on the shaft 112 is a pinion 121 engaging a gear 122 on the shaft 114. The shaft 114 is provided with a pinion 123 meshing with a gear 124 on the main shaft 26.

As already described, the shaft 26 carries the bottle cam 4^a and the cams 78 and 79. It also carries an operating cam 125 which is effective for operating a bell crank 126 connected to the operating rod 6.

It will be understood that the operating mechanism for one head is identical with the operating mechanism for the several other heads and that such apparatus may be duplicated on the shaft 26 as desired. The illustrated machine shows two heads, but it will be understood that any number of heads may be provided as desired.

The frame below the conveyor table 40 is provided with box sides as shown in Figure 6, so that all the operating mechanism may be carried in an oil bath, thus greatly increasing the life of the machine. It is found that in commercial operation there is always some tendency for water to enter the lower parts of the machine in spite of all precautions against its entry and the machine base is therefore provided with a sump 127 in which

the water collects by reason of its being heavier than the oil. A stand pipe 128 is connected to the sump and in operation the water is forced out of this stand pipe as it collects in the sump 127.

70 While I have illustrated a preferred embodiment of the invention, it will be understood that it is not thus limited since the invention may be otherwise embodied within the scope of the following claims.

75 I claim:

1. A bottle filling machine, including a pair of substantially parallel conveyors, bottle filling heads disposed between the conveyors, means for moving the bottles sidewise from one conveyor into alignment with the filling head for the filling operation, and a gripper for moving the bottle out of alignment with the filling head onto the second conveyor, said gripper being adapted to grip the bottle during at least a portion of the filling operation.

80 2. A bottle filling machine having a plurality of heads, a conveyor adapted to move bottles in substantially parallel paths spaced different distances from the heads, means for moving successive bottles from the several paths to points substantially equally spaced from the several heads, and means for moving the bottles successively sidewise relative to the paths from such points into alignment with the filling heads.

85 3. A bottle filling machine having a plurality of heads, a conveyor adapted to move bottles in substantial parallel paths spaced different distances from the heads, means for moving such bottles from the several paths to points substantially equally spaced from the several heads, means for engaging the bottles at such point and moving them sidewise relative to the paths into alignment with the filling heads, and means for continuing the sidewise movement for moving the bottles out of alignment with the filling head.

90 4. A filling machine having a plurality of filling heads, a pair of feeding arms for each head, a conveyor carrying bottles alongside the several heads, means for positioning the conveyed bottles adjacent the heads and between the feeding arms, means for moving the arms relative to one another for gripping the positioned bottles, means for moving the arms together for moving the bottles sidewise into filling alignment with the several heads, and means associated with each head for withholding conveyed bottles from the positioning means for such head.

95 5. Bottle filling apparatus, including a filling head, a pivotally mounted feeding arm, bottle gripping means on said arm, means for moving the arm about its axis to a bottle receiving point, means for supplying bottles to such point, means for moving the arm about its axis to carry the bottle into filling alignment with the head, and means for with- 100

holding bottles from said receiving point until the arm has made a return stroke.

6. Bottle filling apparatus, including a filling head, feeding means having gripping portions which engage the bottle and move it into filling alignment with the head, and means for moving the bottle axially while it is in filling alignment, the bottle moving means being adapted to grip the bottle and move axially therewith during at least a portion of the axial movement.

7. Bottle filling apparatus, including a filling head, feeding means having gripping portions which engage a bottle and move it into filling alignment with the head for filling and thereafter move it out of filling alignment, and means for moving the bottle axially while it is in filling alignment, the feeding means being adapted to grip the bottle and move axially therewith during at least a portion of the axial movement.

8. Bottle filling apparatus, including a filling head, a bottle moving plunger, a supply station alongside the plunger, a shaft substantially parallel with the axis of the head, a bottle feeding arm mounted on the shaft, means for rotating the shaft to cause the arm to feed bottles from the supply station onto the plunger, and means for moving the shaft endwise when the arm is engaging a bottle.

9. Bottle filling apparatus, including a frame, a pair of shafts, a feeding arm on each shaft, means fixed in the frame for causing relative rotation of the shafts to grip a bottle, means for causing substantially simultaneous endwise movement of the shafts relative to the frame while a bottle is gripped, and connections between the first mentioned means and the shafts effective in different endwise adjusted positions of the shafts.

10. Bottle filling apparatus, including a pair of shafts, a feeding arm on each shaft, means for causing relative rotation of the shafts to grip a bottle, means for causing substantially simultaneous endwise movement of the shafts while a bottle is gripped, and means for causing substantially simultaneous rotation of the shafts to move a gripped bottle sidewise.

11. Bottle filling apparatus, including a filling head, a pair of feeding arms, a pair of links connected to each other at one end and having their remote ends pivoted in the arms, means for moving the arms toward one another to grip bottles between the arms and the links, and means for moving the arms together to feed bottles sidewise.

12. Bottle filling apparatus, including a filling head, a pair of feeding arms, a pair of links connected to each other at one end and having their remote ends pivoted in the arms, means for moving the arms toward one another to grip bottles between the arms and the links, means for moving the arms together to feed bottles sidewise, and means

for moving the arms along their axis of rotation to cause axial movement of the gripped bottles.

13. A bottle filling machine, including a filling head, a pair of feeding arms therefor, means for normally urging the arms together to grip the bottles, a cam follower operatively connected to each arm, and a cam for each follower, the cams being adapted to spread the arms to permit entry of a bottle therebetween.

14. A bottle filling machine, including a filling head, a pair of feeding arms therefor, means for normally urging the arms together to grip the bottles, a cam follower operatively connected to each arm, and a cam for each follower, the cams being adapted to spread the arms to permit entry of a bottle therebetween, said cams being further so shaped that the arm urging means may move the arms toward one another after the spreading movement, the followers being free to leave the cams.

15. A bottle filling machine, including a filling head, a pair of feeding arms therefor, means for normally urging the arms together to grip the bottles, a cam follower operatively connected to each arm, and a cam for each follower, the cams being shaped to spread the arms to permit entry of a bottle therebetween, said cams being further so shaped that the arm urging means may move the arms toward one another after the spreading movement, the followers being free to leave the cams, the cams being further adapted to cause movement of the arms sidewise to feed a gripped bottle to the filling head.

16. Bottle filling apparatus, including a filling head, a shaft substantially parallel to the axis of the filling head and carrying a feeding arm, a sleeve around the shaft carrying a cooperating feeding arm, cam followers operatively connected to the shafts and adapted to rotate the same, and cams for the followers, said cams being adapted to separate the arms and to move the arms sidewise.

17. Bottle filling apparatus, including a filling head, a shaft substantially parallel to the axis of the filling head and carrying a feeding arm, a sleeve around the shaft carrying a cooperating feeding arm, cam followers operatively connected to the shafts and adapted to rotate the same, cams for the followers, said cams being adapted to separate the arms and to move the arms sidewise, and means for moving the shafts endwise to cause axial movement of a gripped bottle.

18. Bottle filling apparatus, including a filling head, a shaft substantially parallel to the axis of the filling head and carrying a feeding arm, a sleeve around the shaft carrying a cooperating feeding arm, cam followers operatively connected to the shafts and adapted to rotate the same, cams for the followers, said cams being adapted to separate the arms and to move the arms sidewise, a

plunger for moving bottles axially into the filling head and permitting axial movement of a filled bottle from the head, and a connection between the plunger and the shafts whereby the arms are moved with the plunger.

5 In testimony whereof I have hereunto set my hand.

PATRICK W. SHIELDS.
